UNITED STATES PATENT OFFICE.

THOMAS VEITCH, OF NEW YORK, N. Y., ASSIGNOR OF ONE-HALF TO JOSEPH A. STEINMETZ, OF PHILADELPHIA, PENNSYLVANIA.

STARTING DEVICE FOR INTERNAL-COMBUSTION ENGINES.

1,117,282.

Specification of Letters Patent. Patented Nov. 17, 1914.

Application filed May 24, 1913, Serial No. 769,638. Renewed April 8, 1914. Serial No. 830,535.

To all whom it may concern:

Be it known that I, THOMAS VEITCH, a citizen of the United States, and resident of the city of New York, in the county of New York and State of New York, have invented certain new and useful Starting Devices for Internal-Combustion Engines, of which the following is a specification.

The present invention relates to devices for starting internal combustion engines, and more particularly to means for starting an engine by a non-combustible gas under pressure acting directly upon the working pistons of the engine, the flow of the gas thereto being controlled by a valve operated by and in unison with the engine.

It has been found in practice that starting devices of this type, usually called "air starting devices," are objectionable for the reason that the engine must be turned over a number of times until it continues to run in the ordinary manner by drawing combustible mixture from the carburetor, and that a considerable supply of compressed air must be carried along therefore.

One of the objects of the invention is to obviate these defects, and to provide an air starting device which serves at the same time to form initial combustible charges, the air being caused to act upon that piston which is on its working stroke and the combustible charge being introduced into that cylinder, the piston of which is on its suction stroke.

Another object of the invention is to produce a device of this character which is simple in construction, efficient in operation and which can be readily mounted upon or attached to internal combustion engines of any suitable types.

With these and other objects in view, which will more fully appear as the nature of the invention is better understood, the same consists in the combination, arrangement and construction of parts hereinafter fully described, pointed out in the appended claims and illustrated in the accompanying drawings, it being understood that many changes may be made in the size and proportion of the several parts and details of construction within the scope of the appended claims without departing from the spirit or sacrificing any of the advantages of the invention.

Two of the many possible embodiments of

the invention are illustrated in the accompanying drawings, in which:—

Figure 1 is a diagrammatic view of an internal combustion engine provided with the present invention; Fig. 2 is a vertical section taken through a distributor controlling the flow of a non-combustible fluid under pressure to the cylinders and also that of the combustible charges; Fig. 3 is a plan view of the top plate of said distributor; Fig. 4 is a plan view of the valve of said distributor; Fig. 5 is a vertical section taken through the device for forming the initial combustible charges; and Fig. 6 is a plan view of a modified valve.

Referring now more particularly to Figs. 1 to 5, inclusive, the numeral 10 indicates an internal combustion engine having a plurality of cylinders 11, in the case shown in the drawings four, which are indicated in their order by the numerals I, II, III and IV. The engine diagrammatically represented in the drawings is of the four cycle type, its crankshaft being shown at 12. The pistons of the engine are indicated by the numerals 13. The several cranks of the crankshaft are disposed in such a manner that whenever the piston in the cylinder I is on its working stroke, the piston in cylinder IV is on its suction stroke, and vice versa, and whenever the piston in the cylinder II is on its working stroke, the piston in cylinder III is on its suction stroke, and vice versa.

Thus far the construction and operation of the parts are well known.

For starting the engine, a non-combustible gas under pressure, for instance compressed air, is stored in a reservoir 14, which communicates through a pipe 15 with a distributor 16, said communication being controlled by a cock 17. The distributor comprises a casing 18, closed by a top plate 19, which is provided with a plurality of discharge openings 20. These openings are arranged on a circle and spaced apart equidistantly, their number corresponding to that of the cylinders, or in other words there are provided four discharge openings, spaced 90° apart on a circle. The said openings are denoted in their order by the numerals I', II', IV' and III', and communicate through pipes 21 with the combustion chambers of the cylinders, denoted by

the corresponding Roman numerals. The communication between the casing 18, to which the pipe 15 leads, and the several cylinders of the engine is controlled by a rotary valve 22, preferably of the disk type. This valve is provided with an aperture 23, adapted to register successively in its rotation with the discharge openings 20. The valve is attached to a shaft 24, which is journalized in the casing 18 and in a bracket 25, and to which rotation is imparted by the crankshaft of the engine by the intermediary of bevel gears 26 and 27, the former being keyed to the shaft 24 and the latter to the crankshaft. The ratio of these gears is two to one, whereby the shaft 24 will complete one revolution while the crankshaft makes two complete turns. In the top plate 19 of the distributor casing is furthermore provided a centrally arranged inlet opening 28, registering continuously with a passage 29 in the disk valve 22. This passage extends from the center of said valve toward its periphery and terminates at a point which is disposed diametrically opposite to the aperture 23, thereby registering in succession with the discharge openings 20; more particularly always with that discharge opening which is 180° behind the opening which is in alignment at the time with the aperture 23 in the disk valve. A pipe 30 connects the inlet opening 28 with an initial charge forming device 31. This device comprises a closed receptacle 32, containing a suitable liquid hydrocarbon adapted to be filled in the same through an inlet 33, which is normally closed by a plug 34. On this casing is mounted a cross-shaped member 35, having a substantially horizontal passage 36, to one end of which leads the pipe 30 above referred to, while its other end is connected by means of a pipe 37 with the pipe 15. A conduit 38 extends substantially at right angles to and from the passage 36, and communicates through a pipe 39 with the interior of the receptacle 32, the said pipe extending toward the bottom of said receptacle, but stopping short of said bottom. The passage 36 communicates also through a channel 40 with the receptacle 32, whereby compressed air or fluid flows on top of the liquid hydrocarbon, thereby equalizing the pressure. The size of the mouth of the conduit 38 is adapted to be controlled by a needle valve 41. The operation of this device is as follows: It is to be observed that the valve 22 is rotated as long as the engine is in operation, but, since the cock 17 is turned to its closed position during the normal operation of the engine, the starting device is rendered inoperative. The valve, however, is rotated by and in unison with the crankshaft of the engine, the relation being such that the working chamber of a cylinder communicates

through its respective pipe 21 and the aperture 23 in the valve with the casing of the distributor during the working stroke of the piston in said cylinder, and on the other hand, that cylinder in which the piston is on its suction stroke communicates through its respective pipe 21 and the passage 29 in the valve with the pipe 30. When the engine is caused to come to the full stop, obviously some of the pistons are at or near their upper dead centers and others at or near their lower dead centers, or in other words some of the pistons, when the engine is started, commence or continue their working strokes and others their suction strokes. 70 75 80

To start the engine, the cock 17 is turned to its open position, whereby compressed air flows into the casing 18 and thence through the aperture 23 in the valve to that cylinder, the piston of which is to start its working stroke. The compressed air or other non-combustible fluid under pressure acts upon the said piston, thereby starting the rotation of the engine. At the same time the receptacle 32 receives compressed air through the pipe 37 and the channel 40, and the air or fluid, rushing past the permanently open mouth of the conduit 38, forms a combustible mixture which is carried through the pipe 30 and a pipe 21 into that cylinder, the piston of which is on its suction stroke. As the engine is started, the valve 22 is rotated, its aperture 23 being brought into alignment with the next discharge opening 20 in the series and its passage 29 correspondingly in registering position with the discharge opening diametrically opposite to the same. Compressed air and combustible mixture, respectively, will thus flow into two cylinders. As this compressed air acts upon one of the pistons in said cylinders, the combustible charge which has been drawn during the first half revolution of the crankshaft into a cylinder is compressed, at the proper time ignited, the resulting products of combustion 90 95 100 105 110 115 120 125 130 135 140 145 150 155 160 165 170 175 180 185 190 195 200 205 210 215 220 225 230 235 240 245 250 255 260 vention which lies mainly in the provision of means for supplying a non-combustible fluid under pressure to those cylinders, the pistons of which are on their working strokes, 5 and an initial charge of combustible mixture to those cylinders, the pistons of which are on their suction strokes.

The device herein described has been shown constructed for a four cylinder four 10 cycle engine. Obviously if the cranks on the crankshaft were arranged in another manner relative to each other, the relation between the passage 29 and the aperture 23 in the valve 22 would have to be changed accordingly. The same is true if the engine 15 contains more or less than four cylinders. These changes are, however, within the skill of persons versed in the art and, therefore, it is thought unnecessary to go into a further 20 discussion of the same. The invention can be applied to two cycle engines just as well. A valve for a four cylinder two cycle engine is shown in Fig. 6 of the drawings, differing 25 from the one above described only in that its passage 29 is arranged at 90° to the aperture 23 therein.

What I claim is:—

1. The combination with an internal combustion engine comprising a plurality of 20 cylinders, of a reservoir containing a supply of non-combustible fluid under pressure, a charge forming device communicating with said reservoir, and a distributor connected with said cylinders, reservoir and 25 charge forming device for establishing a communication between said reservoir and said cylinders in succession when their respective pistons are on their working strokes and between said charge forming device 30 and said cylinders in succession when their respective pistons are on their suction strokes.

2. The combination with an internal combustion engine comprising a plurality of 35 cylinders, of a reservoir containing a supply of non-combustible fluid under pressure, a charge forming device communicating with said reservoir, and means connected with said cylinders, reservoir and charge forming 40 device for establishing a communication between said reservoir and said cylinders in succession when their respective pistons are on their working strokes and between said charge forming device and said cylinders in 45 succession when their respective pistons are on their suction strokes.

3. The combination with an internal combustion engine comprising a plurality of 50 cylinders, of a reservoir containing a supply of non-combustible fluid under pressure, a charge forming device communicating with said reservoir, and a distributor actuated by and in unison with said engine connected with said cylinders, reservoir and 55 charge forming device for establishing a

communication between said reservoir and said cylinders in succession when their respective pistons are on their working strokes and between said charge forming device and said cylinders in succession when their respective pistons are on their suction strokes. 70

4. The combination with an internal combustion engine comprising a plurality of cylinders, of a reservoir containing a supply of non-combustible fluid under pressure, 75 a charge forming device communicating with said reservoir, and means actuated by and in unison with said engine connected with said cylinders, reservoir and charge forming device for establishing a communication between said reservoir and said cylinders in succession when their respective pistons are on their working strokes and between said charge forming device and said cylinders in succession when their respective pistons are on their suction strokes. 80

5. The combination with an internal combustion engine comprising a plurality of cylinders, of a reservoir containing a supply of non-combustible fluid under pressure, 85 a charge forming device communicating with said reservoir, a casing connected with said cylinders, reservoir and charge forming device, and a valve in said casing for establishing a communication between said reservoir and said cylinders in succession when their respective pistons are on their working strokes and between said charge forming device and said cylinders in succession when their respective pistons are on their suction strokes. 90

6. The combination with an internal combustion engine comprising a plurality of cylinders, of a reservoir containing a supply of non-combustible fluid under pressure, a charge forming device communicating with said reservoir, a casing connected with said cylinders, reservoir and charge forming device, and a rotary valve in said casing for establishing a communication between said reservoir and said cylinders in succession when their respective pistons are on their working strokes and between said charge forming device and said cylinders in succession when their respective pistons are on their suction strokes. 105

7. The combination with an internal combustion engine comprising a plurality of cylinders, of a reservoir containing a supply of non-combustible fluid under pressure, a charge forming device communicating with said reservoir, a casing connected with said cylinders, reservoir and charge forming device, and a valve actuated by and in unison with said engine in said casing for establishing a communication between said reservoir and said cylinders in succession when their respective pistons are on their working strokes and between said charge forming device and said cylinders in succession when 110

their respective pistons are on their suction strokes.

8. The combination with an internal combustion engine comprising a plurality of 5 cylinders, of a reservoir containing a supply of non-combustible fluid under pressure, a charge forming device communicating with said reservoir, a casing connected with said cylinders, reservoir and charge forming 10 device, and a rotary valve actuated by and in unison with said engine in said casing for establishing a communication between said reservoir and said cylinders in succession when their respective pistons are on their 15 working strokes and between said charge forming device and said cylinders in succession when their respective pistons are on their suction strokes.

9. The combination with an internal 20 combustion engine comprising a plurality of cylinders, of a charge forming device, a casing adapted to receive a non-combustible fluid under pressure provided with a plurality of discharge openings, said openings 25 being in communication with said cylinders, said casing being also connected with said charge forming device, and a valve in said casing for opening said discharge openings in succession to establish a communication 30 between said casing and said cylinders as their respective pistons are on their working strokes and between said charge forming device and said cylinders in succession as their respective pistons are on their suction 35 strokes.

10. The combination with an internal combustion engine comprising a plurality of cylinders, of a charge forming device, a casing adapted to receive a non-combustible 40 fluid under pressure provided with a plurality of discharge openings, said openings being in communication with said cylinders, said casing being also connected with said charge forming device, and a rotary valve 45 in said casing for opening said discharge openings in succession to establish a communication between said casing and said cylinders as their respective pistons are on their

working strokes and between said charge forming device and said cylinders in succession as their respective pistons are on their suction strokes.

11. The combination with an internal combustion engine comprising a plurality of cylinders, of a charge forming device, a 50 casing adapted to receive a non-combustible fluid under pressure provided with a plurality of discharge openings, said openings being in communication with said cylinders, said casing being also connected with said charge forming device, and a valve actuated by and in unison with said engine in said casing for opening said discharge openings in succession to establish a communication between said casing and said cylinders as 55 their respective pistons are on their working strokes and between said charge forming device and said cylinders in succession as their respective pistons are on their suction strokes.

12. The combination with an internal combustion engine comprising a plurality of cylinders, of a charge forming device, a casing adapted to receive a non-combustible 70 fluid under pressure provided with a plurality of discharge openings, said openings being in communication with said cylinders, said casing being also connected with said charge forming device, and a rotary valve actuated by and in unison with said engine in said casing for opening said discharge openings in succession to establish a communication between said casing and said cylinders as their respective pistons are on their working strokes and between said charge forming device and said cylinders in succession as their respective pistons are on their suction 75 strokes.

Signed at New York, in the county of New York and State of New York, this 90 17th day of May, A. D. 1913.

THOMAS VEITCH.
